BOTTLE CAPPING MACHINE

Walter A. Barrett, Fort Wayne, Ind.

Application March 8, 1949, Serial No. 80,146

4 Claims. (Cl. 226—92)

1

This invention relates to a bottle capping machine. More specifically it relates to a machine for applying a coverall type of cap to a milk bottle.

It is an object of the invention to provide means conditioned by the bottle capping operation to actuate a mechanism for positioning a new cap for the subsequent capping operation.

Another object of the invention is to provide means for retarding the operation of the cap positioning mechanism to permit removal of the capped bottle prior to positioning of the next cap.

It is another object of the invention to provide a capper which is smooth and relatively silent in operation.

A further object of the invention is to provide a capper which is positive in operation.

These and other objects will become apparent from a study of this specification and the drawings which are attached hereto and made a part hereof and in which:

Figure 1 is an elevation, partly in section, of the capper supporting means.

Figure 2 is a sectional view of the capper with the bottle starting to rise to capping position.

Figure 3 is a view similar to Figure 2 except that the bottle is in the full capping position.

Figure 4 is a view similar to Figures 2 and 3 but showing the bottle descending and cap positioning slide returning toward the Figure 2 position.

Figure 5 is a top view of the capping machine.

Figure 6 is an elevation in section of the dashpot piston.

Referring to Figure 1, the numeral 1 refers to the table which rotates with shaft 3 on suitable bearings (not shown). A sleeve 5 is fixed to the table, extends upwardly therefrom and is internally threaded to receive a height adjusting screw 7.

The capper support 9 is fixed to the upper end of the screw and carries a locking sleeve 11 which telescopes over sleeve 5 to which it is attached by a locating screw 13 which enters a slot 15 in sleeve 5 and a clamping screw 17.

The support 9 has diametrically opposed pairs of arms 19—21, 23—25 which are perforated to receive slidable capper shafts 27. Since both cappers are constructed alike only one will be described and the same numerals will indicate similar parts of each.

The portion of shaft 27 between arms 19—21 is encircled by a compression spring 29. A collar 31 is fixed to the shaft between the bottom of

2

the spring 29 and arm 21 by means of pin 33.

A piston or plunger 35 is formed on the lower end of the shaft and, as shown particularly in Figure 6 it is provided with a bleeder port 37 which passes axially through it.

A second bore 39 is formed axially through the piston and is counterbored at 41. A ball valve 43 is seated in the counterbore and urged by a spring 45 to close the bore. A ring 47 is pressed in the counterbore to hold the spring in place.

The cylinder body 49 is provided with a cylinder bore 51 to receive the piston and with an elongated sleeve 53 which is slidably mounted on the shaft 27. An annular ring 54 riding in an annular groove 56 in sleeve 53 prevents leakage between the shaft and sleeve. A compression spring 58 encircles shaft 27 between the lower side of arm 21 and the end of sleeve 53. The sleeve is provided with elongated slots 55 which provide clearance for a pin 57 which projects through the shaft 27.

A head 59 is fixed to the cylinder body to close the cylinder and has a cap magazine tube 61 fixed to it.

A circular cap pressing groove 63 is formed in the head opposite the piston.

The magazine tube 61 is provided with a bore 65 of a size to receive the caps 67 and a counterbore 69 which is adapted to receive a cap packaging tube 71.

A guide is mounted on the head 59 and comprises a guide plate and a boss 75 provided with a bore 77 which is aligned with groove 63. The upper and lower sides of the bore are countersunk. The guide plate 79 extends from the bore laterally under and beyond the magazine.

The cap positioning slide 81 is mounted for reciprocation on the guide plate between a position as shown in Figure 3 where it is retracted to receive a cap from the magazine and the position of Figure 2 in which it has positioned the cap in place over bore 77 where the cap will be held by fingers 83.

Said fingers are pivotally mounted at 85 on the body 49 and have projections 87 which enter holes 89 in the guide 73. A spring 91 urges the fingers toward cap supporting position.

As shown in Figure 1, the projections are inclined upwardly so as to be cammed away from the cap by the bead of the bottle.

The slide is provided with a stub shaft 93 on each side. A link 95 is rotatably mounted at one end on each shaft and at the other end on a bell crank 97 which is pivoted on shaft 99 supported in a boss 101 on the magazine. The other arm

of the lever is slotted at 103 to receive the ends of pin 57.

The bottles 104 to be capped are carried on platforms 105 which rotate with the capper support 9 and are axially aligned with the capping groove 63 and the bore 77 of the guide 75. The platform supporting means 107 is also capable of moving up and down over a fixed cam 109 when the actuating roll 111 encounters the cam.

Any suitable platform supporting and bottle moving mechanism may be used.

Operation

As shown in Figure 5, the bottles enter the capping machine in the direction of the arrow A and mount the platforms 105 which are in axial alignment with guide bores 77 and cap grooves 63. The platforms revolve about the axis of shaft 7 at the same velocity as the cappers and, assuming that a cap 67 is held positioned over the bottle as shown in Figure 2, as the roller 111 rides up on the cam 109, the bead of the bottle will enter the guide bore 77, spread fingers 87, pick up the cap and press it into the groove 63 on the head 59 and over the bead of the bottle to attach it thereto.

As the roller continues to ride up the cam, the entire capper mechanism slides upwardly on the shaft 27 and piston 35 which are held fixed.

As the cylinder 51 is displaced relative to the piston, the liquid which fills the cylinder below the piston is pressurized and opens valve 43 so that it can pass through the piston into the expanding chamber on the other side thereof. The valve port is large enough to permit a rapid passage of the liquid in this direction.

The spring 58 is compressed, reaching its maximum when the high point of the cam is reached by the roller as shown in Figure 3.

It will be seen that during the movement of the parts from the Figure 2 to the Figure 3 position, the pivot pin 99 of the bell crank 97 has been raised relative to the fixed pin 57. This rotates the crank clockwise and thrusts the links 95 and slide 81 to the left beyond the caps in the magazine so that a new cap may drop down on the guide 79.

As the roller 111 rides down the cam 109, the capped bottle will move away from the head 59 which moves downwardly under the action of spring 58 but is restrained by the liquid which is pressurized in the upper chamber and which can escape to the expanding lower chamber only through the restricted port 37.

Thus the return of the slide with the new cap from the Figure 3 to the Figure 2 position is retarded until the capped bottle has fallen below the level of the position to be occupied by the new cap.

At the completion of the stroke, that is when the parts again occupy the Figure 2 position, it will be seen that the new cap will be in position on the fingers 87 in alignment with the guide bore 77 and groove 63 ready for the next bottle.

The capped bottle leaves the capping machine along the line of the arrow B.

The rate of return of the cylinder under the action of the spring 58 depends upon the viscosity of the oil used in the cylinder and the size of the port 37 and may therefore be regulated to suit the requirements of the machine. That is, the action may be accelerated by opening the port if the machine speed requires it. The important point is that the slide must not be re-

turned so rapidly that the new cap will be forced against that on the newly capped bottle, otherwise the new cap may be distorted so that it will not receive the next bottle or the bottle just capped may have the cap partly removed or both.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claims.

What I consider to be new and desire to protect by Letters Patent of the United States of America is:

1. A bottle capper comprising a fixed shaft, a sleeve slidable up and down thereon to and from a bottom position, resilient means for urging the sleeve to the down position, cap presser means on the sleeve, a cap magazine mounted on the sleeve, means mounted on the sleeve for abstracting a cap from the magazine and positioning it in alignment with the presser means, means for reciprocating a bottle toward and away from the presser means to actuate the sleeve and install the cap on the bottle and means connecting said shaft sleeve, the positioning means for actuating the latter to cap abstracting position when the sleeve is up and to cap aligning position when the sleeve is down and dashpot means for reducing the rate of restoration of the sleeve below that of the withdrawal of the bottle to prevent interference between the bottle and the cap being positioned.

2. A bottle capper comprising a fixed shaft, a piston on the shaft, a sleeve slidably mounted on the shaft and having a fluid filled cylinder for the piston, a spring disposed to urge said sleeve and cylinder downwardly with respect to the shaft and piston, a restricted port in the piston, a valve controlled larger port in the piston, means forming a passage for the fluid from the lower side of the piston through the larger port, means for preventing the return of liquid through the passage, cap presser means, a cap magazine and cap shifting means all mounted on the sleeve and means connecting said shaft sleeve and shifting means for operating the latter to move a cap from the magazine and position it in alignment with the presser means on the down stroke of the sleeve.

3. A bottle capper comprising a fixed shaft, a piston on the shaft, a sleeve slidably mounted on the shaft and having a fluid filled cylinder for the piston, a spring disposed to urge said sleeve and cylinder downwardly with respect to the shaft and piston, a restricted port in the piston, a valve controlled larger port in the piston, means forming a passage for the liquid from the lower side of the piston through the larger port, means for preventing the return of liquid through the passage, cap presser means, a cap magazine and cap shifting means all mounted on the sleeve and means connecting said shaft sleeve and shifting means for operating the latter to move a cap from the magazine and position it in alignment with the presser means on the down stroke of the sleeve and to position the shifting means to receive another cap from the magazine on the up stroke of the sleeve.

4. A bottle capper comprising a fixed shaft, a piston on the shaft, a sleeve slidably mounted on the shaft and having a fluid filled cylinder for the piston, means for passing fluid slowly

from one side of the piston to the other, a spring disposed to urge the sleeve downwardly, cap presser means for the sleeve, a cap magazine and cap shifting means mounted on the sleeve, said shifting means comprising a guide, a slide mounted for movement on the guide from a position below and at one side of the magazine to a position below and at one side of the presser means whereby to abstract a cap from the magazine and position it in alignment with the presser means, a lever pivotally mounted on the sleeve, a pin on the shaft engaging one end of the lever, and link means connecting the other end of the lever with the slide, and means for reciprocating a bottle toward and away from the presser means to lift the sleeve and install the cap on the bottle.
